UNITED STATES PATENT OFFICE.

FRED. C. SCHOENTHAL, OF BUFFALO, NEW YORK.

DISK WHEEL.

1,382,556.

Specification of Letters Patent. Patented June 21, 1921.

Application filed November 7, 1919. Serial No. 336,337.

To all whom it may concern:

Be it known that I, FRED. C. SCHOENTHAL, a citizen of the United States, residing at Buffalo, in the county of Erie and State of New York, have invented certain new and useful Improvements in Disk Wheels; and I do hereby declare the following to be a full, clear, and exact description of the same, such as will enable others skilled in the art to 10 which it appertains to make and use the same, reference being had to the accompanying drawings, and to figures of reference marked thereon, which form part of this specification.

15 Like figures of reference refer to like parts.

This invention relates to disk wheels for vehicles.

One of the objects of this invention is to 20 provide a disk wheel wherein a single sheet of metal forms the wheel disk, which forms the function of spokes, the felly of the wheel and part of the rim thereof.

Another object is to provide a sheet metal 25 disk wheel having sheet metal reinforcing parts about the hub, which are of such shape as to easily lend themselves to the processes of sheet metal stamping. And a further object is to provide an auxiliary disk in connection with the main disk of the wheel, which auxiliary disk is provided with a peripheral recess adapting the peripheral edge of the auxiliary disk to abut against the surface of the main disk, and also to have the 30 recess contain some impervious material which shall serve to exclude water from between the main disk and auxiliary disk.

The form of disk wheel which is the subject of this application, is an improvement 40 on the one which is the object of my application filed Aug. 23, 1919, under the Serial Number 319,396, and differs particularly therefrom in the fact that in this invention of a disk wheel, part of the rim, the felly and 45 the main disk are all incorporated in one sheet of metal.

With these and other objects my invention consists in certain features of construction, one embodiment of which is illustrated in 50 the drawings, is hereinafter described, its construction is explained, and what I claim is set forth.

In the drawings,

Figure 1 is a front plan view of a vehicle

disk wheel embodying my invention, having 55 part of the wheel broken away to more fully illustrate its construction.

Fig. 2 is a section of the wheel shown in Fig. 1, taken on the line X—X thereof.

Fig. 3 is a perspective view of one of the 60 bridging pieces used to reinforce the felly at the bolt connection of a rim part.

Fig. 4 is a plan of the auxiliary reinforcing disk.

Fig. 5 is a section taken on the line X—X 65 of Fig. 4.

Fig. 6 is a plan of the backing plate.

Fig. 7 is a section taken on the line X—X of Fig. 6.

Fig. 8 is a plan of the spacing and reinforcing ring.

Fig. 9 is a section taken on the line X—X of Fig. 8.

Fig. 10 is an enlarged section of the 75 spacing thimble used between the auxiliary disk and the backing plate at the clamping studs.

Fig. 11 is an enlarged section of the flared portion of the felly and rim at the bolt hole.

Fig. 12 is a section of a modified form of 80 rim to that shown in Figs. 1 and 2.

In the figures, there is shown the usual form of axle 1, upon which the wheel is mounted, shown having a hub formation 2, of the Ford type, held upon the axle 1, by 85 the nut 3. The cap 4 in threaded engagement with the hub 2, covers the nut 3. Bolted to the flange 5, by the bolt 6 is a brake drum 7, which bolt 6, with five others firmly secures a hub bed plate 8, to the 90 flange 5. This bed plate 8, has an angular recess at 9, against which is fitted an auxiliary disk 10, having also a bearing at 11, against the bed plate 8 near the hub 2. There is a cylindrical portion at 12, having 95 a bearing on the bed plate 8. This disk is stiffened by radial ribs 10^a. At the periphery 10^b of the disk 10 is an annular recess 10^c filled with an impervious material 10^d acting as a seal between the main and auxiliary 100 disks to exclude water therebetween. A reinforcing plate 13, co-fitting the auxiliary disk 10, near the recess 9, is provided. This reinforcing disk has a flange 14, which together with the cylindrical portion 15, of the auxiliary disk 10, forms an abutment for the 105 inner part of the main disk 16, which is forced in contact therewith, by means of the

- circular clamping plate 17, held in place by the stud 18, with the nut 19. The stud 18 has a head 20, fitting into a recessed portion 21, of the bed plate 8. A stud 18 is provided 5 with a thimble 22, having a flange 23. Part of the thimble 22 is partly in threaded engagement with the stud 18, and is screwed down tight, shoulderering against the bed plate 8, to assist in holding the stud in place 10 on the bed plate 8, and acts as a spacer between the auxiliary disk 10, and the bed plate 8, where the studs 18 pass through to engage the nut 19, and also to form a rigid backing to the parts which are drawn together 15 by the nut 19. There are three of these studs 18 equally spaced about the hub. The main disk 16 is shown in section to have an annular pocket 24 on the front thereof, from which the metal diverges peripherally. 20 The metal is shown to extend peripherally beyond the pocket and to turn in the opposite direction forming an annular pocket 25 on the rear side of the wheel, and in so doing, there is formed a felly for the wheel. 25 The metal continues peripherally until part 26 of the rim is formed. Coöordinated with the part 26 of the rim is the rim ring part 27, which is bolted to the felly 25, by means of bolts and nuts 28 and 29, respectively, the 30 heads 30 of which bolts pass through the body of a bridge piece 31, which bridge piece 31, is electrically welded into place in the felly 25^a. A cotter pin 32 is provided to secure the head 30 from turning within the 35 bridging piece 31. There is also provided a tube 33 incorporated in the felly portion 25^a. In Figs. 1 and 2 is shown a clench or inturned flange form of rim, while in Fig. 12 the section shows the rim flanges 26^b and 40 27^b flared outward.
- It will be noted that the principal part of the rim is shown as integral with the felly and main disk, and that the form herein shown in section, lends itself easily to the 45 operations of stamping. Where the ring 27 is incorporated with the felly 25^a, there are shown, in enlarged section in Fig. 11, at the holes provided for the passage of the bolts 28, out-turned flanges 25^b, upon the felly 50 portion 25^a, which flanges 25^b co-fit into the flanges 27^a on the ring 27. The flanges 25^b on the felly portion 25^a do not project all the way through the flanges 27^a, thereby permitting the nut 29 to have a full bearing 55 upon the edge of the flange 27^a only, in drawing the parts together. These flanges 25^b and 27^a, interfitting as they do, relieve the bolts 28 of all transverse strain. Modifications of the one embodiment of my 60 invention herein shown, may be made without departing from the spirit and scope of the said invention. I therefore do not wish to be confined to this one embodiment.
- Having described my invention, I claim,
- 65 1. In a sheet metal disk wheel having a hub and a hub flange, a backing plate concentrically positioned upon said hub and fixed to said flange, an auxiliary disk in shouldered engagement with said backing plate, a main disk spaced from said auxiliary disk at the contact of the latter with said backing plate, and in fixed contact with said auxiliary disk near its periphery, a reinforcing ring between said main disk and said auxiliary disk to strengthen the said 70 wheel in abutting relation of the parts, a clamping plate concentrically positioned upon said hub, in bearing contact with said main disk, having a diameter sufficient to have a direct bearing opposite said reinforcing ring and said auxiliary disk, means holding said bearing and said backing plates 75 in clamped relation.
2. In a sheet metal disk wheel for vehicles, a hub, a main disk fixed to said hub, forming the body of a wheel, said main disk terminating in a wheel rim part, an auxiliary rim ring fixed to said rim part, and with the same completing the wheel rim, a sheet metal auxiliary bracing disk seated on 80 said hub, and having a peripheral bearing contact with said main disk, a peripheral recess on said auxiliary disk, and impervious means occupying said peripheral recess, 85 contacting said main disk forming a water 90 tight joint.
3. In a disk wheel the combination of a hub, a hub flange, a backing plate on said hub and fixed to said flange and having an annular recess, an auxiliary disk in engagement with the recess of said backing plate and also bearing against it near said hub, a main disk in contact with said auxiliary disk near its periphery and near the hub at its contact with the recess of said backing plate, and a clamping plate on said hub and bearing against said main disk whereby portions of said main and auxiliary disks are 100 clamped by said clamping plate against said backing plate.
4. In a disk wheel the combination of a hub, a hub flange, a backing plate on said hub and fixed to said flange and having an annular recess, an auxiliary disk in engagement with the recess of said backing plate 105 and also bearing against it near said hub, a main disk in contact with said auxiliary disk near its periphery and near the hub at its contact with the recess of said backing plate, a clamping plate on said hub and bearing against said main disk whereby portions of said main and auxiliary disks are clamped by said clamping plate against said 110 backing plate, thimbles between said auxiliary disk and said backing plate and studs 115 in said thimbles by which said plates are rigidly secured together.
5. In a disk wheel, a backing disk having an annular recess, an auxiliary disk seated in said recess, a main disk against which 120
- 130

bears the periphery of said auxiliary disk and radial strengthening ribs in said auxiliary disk.

6. In a disk wheel, a backing disk having an annular recess, an auxiliary disk seated in said recess, a main disk against which bears the periphery of said auxiliary disk and radial strengthening ribs in said auxiliary disk between the contacting portions thereof.

7. In a disk wheel, a main disk, an auxiliary disk, a backing disk, having an an-

nular recess adjacent its periphery in which said auxiliary disk seats, an annular flange bearing against said auxiliary disk near the 15 wheel hub and a plurality of thimbles between said auxiliary and backing disks.

8. A disk wheel made up of a plurality of disks comprising a main disk, an auxiliary disk bearing at its periphery against said 20 main disk and a backing disk bearing at its periphery against said auxiliary disk.

FRED. C. SCHOENTHAL.
